WASHABLE GAUNTLET GLOVE

Burr R. Skinner, Aberdeen, S. Dak.

Application July 20, 1932. Serial No. 623,574

1 Claim. (Cl. 2—162)

This invention relates to a washable gauntlet glove or mitten adapted to be used as a protection to the hands of those handling machinery or equipment or various materials and repeatedly in a cleanly and sanitary manner, the invention having reference more particularly to a glove having a detachable gauntlet.

An object of the invention is to provide a washable gauntlet glove of such construction as to be adapted to be comfortable to the user thereof and repeatedly used at small cost without requiring frequent renewals or replacements due to wear and tear, but permitting economical replacement of the more important parts and the saving of other parts for further use.

Another object is to provide an improved washable gauntlet glove of such construction as to be adapted to be manufactured inexpensively and of low-price material, particularly the glove or part inevitably subjected to the greater amount of wear both in practical use and in laundering operations or processes.

A further object is to provide an improved washable canvas or woven glove having a relatively stiff detachable gauntlet adapted to be used during long periods of time and permitting simple and inexpensively cleansing of the surface thereof when desired.

A still further object is to provide a durable and inexpensive glove that shall be of such construction as to be adapted to be used by railway trainmen, enginemen, or other railway workmen, and which may be advantageously worn or used by many classes of workers desiring protection to their hands.

A still further object is to provide an improved glove and interchangeable gauntlet of the worker's type having structural features conducive to the conservation of material and labor and the ultimate cost of protection of the hands of users, and which will be likely to prove to be durable and economical in use.

With the above-mentioned and other objects in view, the invention consists in a flexible glove or mitten and a relatively stiff gauntlet or cuff detachably secured thereto, the glove or mitten part being composed of material suitable to be cheaply laundered, the detachable part being composed of material impervious to water, the two parts being provided with interco-operating fastening devices; the invention consisting also further in the parts and the combinations and arrangements of parts as hereinafter particularly described and further defined in the claims appended hereto.

Referring to the accompanying drawing,—Figure 1 is an elevational view of the gauntlet glove constructed substantially in accordance with the invention; Fig. 2 is a fragmentary back view of the preceding figure; Fig. 3 is a front view of the glove minus the gauntlet; Fig. 4 is a plan view of the improved gauntlet unfolded; Fig. 5 is an elevational view of the gauntlet; Fig. 6 is a fragmentary detail of the gauntlet on an enlarged scale having one type of fastener device thereon; Fig. 7 is a fragmentary longitudinal section of the gauntlet on an enlarged scale to plainly show the fastener device as applied thereto; Fig. 8 is a perspective view of the fastener device; Fig. 9 is an elevational view of the complete glove and gauntlet having a different form of fastener device, the wrist portion of the glove being represented as turned over to fully expose the fastener device; and Fig. 10 is a fragmentary detail on an enlarged scale illustrating the modified form of fasteners.

Similar reference characters in the different figures of the drawing indicate corresponding elements or features of construction herein referred to in detail.

The glove or that part which is designed to cover and protect the hand is composed of suitable flexible material such as canvass or woven cotton and for descriptive purposes is referred to as having a palm portion 1 and a back portion 2 to constitute an article of utility, the glove having a wrist portion 3, a thumb portion 4 and a suitable number of finger portions 5. The finger portion of the article may be modified so as to be classified as a mitten. The wrist portion 3 may be variously equipped for attachment with a suitable separate cuff, and in one form of fastener has eyelets or perforations 6 finished with needle-work so as to have an entirely flexible article and free from metallic fastener parts likely to interfere with laundering machinery or wringers, or likely to become distorted by a wringer.

A suitable gauntlet or cuff comprises a layer 7 of imitation leather or other material and a similar layer 8 superimposed and a suitable number of eyes or loops 9 fastened thereto, each loop having bases 10 and 11 arranged between the layers and the loops projecting through slits in the outer layer. One marginal portion of the inner layer 7 is turned over the adjacent edge of the outer layer to form a binding strip 12, the larger end of the gauntlet being likewise provided with a binding strip 13. As partly completed the gauntlet has two edges 14 and 15 which are brought together and suitably stitched or other-

wise secured together, a row of stitching 16 through the strip 12 securing it in place and so arranged as to secure the bases 10 in place. The gauntlet has another row of stitching 17 so arranged as to secure the bases 11 in place between the layers of material; and the layers of material may be further secured together by other lines of stitching 18. The gauntlet is removably secured to the wrist portion of the glove by first 10 drawing the wrist portion over the smaller end of the gauntlet and inserting the loops 9 in the eyelets 6, passing a lacing string 19 through the loops so as to encircle the wrist portion of the glove, and connecting the ends of the lacing 15 string together by means of a suitable bow-knot 20.

When desired, the two parts may be secured together by the type of device commonly known as a snap fastener comprising a base plate 21 sewed 20 to the inner side of the wrist portion of the glove and having each a socket 22, the outer side of the gauntlet having a corresponding device comprising a base plate 23 sewed to the material of the gauntlet and having a stud 24 thereon to be received in the socket. 25

In practical use the gloves are used until they become soiled or greasy and are readily washed or laundered following the removal of the gauntlet therefrom, the gauntlet, being readily cleaned by hand so as to remove greasy matter or other fouling substances that may accumulate thereon incidental to the utilization of the article. Thus the gauntlet may be readily kept in good condition and outlast many of the fabric gloves which being inexpensive and liable to suffer from long use and wear, may be repeatedly replaced by new gloves or by spare laundered gloves. 80 85

What is claimed is:

In a gauntlet glove, the combination with a glove part having eyelets in a portion thereof, 90 of a cuff part composed of superimposed layers of material having smooth faces impervious to moisture, said layers being stitched together, and loops inserted through the outer one of said layers and having each a base integral with each of opposite ends thereof secured between said layers, said cuff part being insertable partially into said glove part to insert said loops into said eyelets for receiving a lacing string. 95
